UNITED STATES PATENT OFFICE.

PERCY TARBUCK, OF LONDON, ENGLAND, ASSIGNOR TO THE HARDEN STAR
LEWIS & SINCLAIR COMPANY, (LIMITED,) OF SAME PLACE.

EJECTOR OIL-VAPOR LAMP.

SPECIFICATION forming part of Letters Patent No. 416,652, dated December 3, 1889.

Application filed November 30, 1888. Serial No. 292,254. (No model.) Patented in England January 14, 1888, No. 624; in France October 18, 1888, No. 193,615; in Belgium October 26, 1888, No. 83,743; in Cape of Good Hope December 14, 1888; in New South Wales December 27, 1888, No. 1,140; in South Australia December 27, 1888, No. 1,203; in Italy January 15, 1889, Vol. XLVIII, 156; in Queensland January 16, 1889, No. 663; in India January 16/23, 1889, No. 116/138; in Spain February 12, 1889, No. 8,952, and in Austria-Hungary May 4, 1889, No. 44,088 and No. 65,484.

To all whom it may concern:

Be it known that I, PERCY TARBUCK, a citizen of England, residing at 23 St. Swithin's Lane, in the city of London, England, have 5 invented a new and Improved Ejector Oil-Vapor Lamp, (for which I have obtained patents in Great Britain, dated January 14, 1888, No. 624; in France, dated October 18, 1888, No. 193,615; in Belgium, dated October 26, 1888, No. 83,743; in Cape of Good Hope, dated December 14, 1888, Folio 492; in New South Wales, dated December 27, 1888, No. 1,140; in South Australia, dated December 27, 1888, No. 1,203; in Italy, dated January 15, 1889, Vol. XLVIII, 156; in India, dated January 16/23, 1889, No. 116/138; in Spain, dated February 12, 1889, No. 8,952; in Austria-Hungary, dated May 4, 1889, No. 44,088/65,484, and in Queensland January 16 and April 25, 20 1889, No. 663,) of which the following is a specification.

This invention relates to a lamp suited for producing a large and brilliant flame available in exposed situations by the ejector action of an air-jet on the vapor or gases generated from oil by heat in the lamp itself.

The accompanying drawing is a vertical section of the lamp.

Its lower part is a vessel divided by a horizontal partition A into two compartments. The lower compartment B is supplied with air under pressure by a pipe C from any suitable air-compressing apparatus. The upper compartment D is supplied with oil from a cistern E, which is provided with a float cock or valve governing a pipe F, leading from an oil-reservoir, which may be at a distance, so as to be removed from proximity to the flame of the lamp. By means of the float cock or 40 valve the level of the oil in the compartment D is maintained approximately uniform.

In the center of the partition A is a nozzle or jet-tube G, which projects a little above the oil in D, and which has its lower mouth governed by a screw-plug H, so that a greater or less current of compressed air can be made to issue as a jet from G.

A conical cover K, open at the top, has through it near its lower edge a number of small holes k, for admitting a small supply of air to the compartment D, and over this cover is placed a hood L, of size larger than K, so that there is an annular air-passage between K and L. The oil in the compartment D being kindled, and receiving a little supply of air through the holes k, burns with a lambent flame over the surface of the oil, generating vapor or gases therefrom. The jet of air through the nozzle G causes the combustible gaseous fluid mixed with air to rush through the mouth of the cover K, and, additional air meeting it there, the whole, when kindled, produces a high and brilliant flame. As the cover K soon becomes heated, the oil vapor and gases are generated in considerable quantity and are heated as they ascend in K, causing the lamp shortly to attain its maximum illuminating-power.

Having thus described the nature of this invention and the best means I know of carrying the same into practical effect, I claim—

1. A vapor-burning lamp consisting of a vessel divided by a horizontal partition into an upper oil-containing compartment adapted to receive oil from a cistern and a lower compressed-air compartment having a pipe for connecting with a source of compressed air, a conical cover resting on the vessel, having an open top and provided at its base with a series of perforations arranged above the said vessel, an air-jet tube supported by said horizontal partition rising therefrom and communicating through the same with the compressed air in the lower compartment to force the combustible gaseous fluid upward through the open top of the conical cover, and a plug or valve which governs the quantity of compressed air passing from the compressed-air compartment into the jet-tube, substantially as described.

2. A vapor-burning lamp consisting of a vessel divided by a horizontal partition into two compartments, the upper one being an oil-compartment and the lower one being an

air-compartment and having a pipe to connect it with a source of compressed air, a conical cover having a perforated base and mounted on the vessel, a conical hood located 5 over the cover, separated therefrom by a surrounding space and open at its base to admit air to the perforated base of said cover, and an air-jet nozzle supported by and rising from the partition communicating through 10 the latter with the compressed-air compartment and serving to force the combustible gaseous fluid upward through the open tops of the cover and hood, substantially as described.

In testimony whereof I have signed my name to this specification, in the presence of two subscribing witnesses, this 14th day of November, A. D. 1888.

PERCY TARBUCK.
